Attorney

UNITED STATES PATENT OFFICE.

JOHN H. JENCKS, OF WATERBURY, CONNECTICUT.

CUTTING-PLIERS.

SPECIFICATION forming part of Letters Patent No. 276,417, dated April 24, 1883.

Application filed October 5, 1882. (No model.)

To all whom it may concern:

Be it known that I, JOHN H. JENCKS, of Waterbury, in the county of New Haven and State of Connecticut, have invented certain Improvements in Cutting-Pliers, of which the following is a specification.

The object of this invention is to provide to nippers, cutting-pliers, &c., detachable side cutters so constructed and applied that the opposed cutting-edges of the two side cutters shall always be directly in the same plane—that is to say, for all practical purposes exactly coincident—to insure their most perfect cutting action, and also so that the said cutters may be readily detached and replaced—as, for example, when dulled, defaced, or injured; and it comprises certain novel combinations of parts whereby this object is effectually secured, the cutting-edges being very firmly retained in position when in use, and capable of being readily started from their sockets by force properly applied.

Figure 1 is a side view of cutting-pliers fitted with side cutters constructed according to my said invention. Fig. 2 is a central longitudinal transverse sectional view thereof. Fig. 3 is a detail sectional view, on a larger scale, through one of the jaws and illustrating the manner in which the cutters are applied in place. Figs. 4 and 5 are detail views, on a like scale, of the cutters. Fig. 6 is a detail view, on a like scale, showing one of the sockets which secure the cutters; and Fig. 7 is a detail view, on a like scale, taken in a plane at right angles to Fig. 6.

The opposite jaws A of the pliers are furnished at one side with sockets *a*, the socket in one jaw being opposite that in the other. The jaws themselves may be of any ordinary or suitable construction, and their extremities may be formed into nipping-jaws *b*, when desired. The jaws themselves may be operated by suitable handles or other means, which, being well known in the construction of nippers, cutting-pliers, &c., need not be here described. Each of the sockets *a* may be somewhat broader at its front portion, *c'*, than at its back *e'*. Furthermore, each of the said sockets has its inner end recessed in semi-dovetail form, as shown at *g'* in Fig. 6, and its inner corners of rounded contour, as indicated at *i* in Fig. 1.

Furthermore, each socket, taken from end to end, is of dovetail form, as indicated more clearly at *f'* in Fig. 7.

The cutters B, one for each of the sockets aforesaid, have their rearmost edges, their bottom or inner sides, their end portions, and their innermost corners shaped to correspond with and fit snugly upon the corresponding portions or internal surfaces of the sockets. The inner edge of each cutter is of course brought to a suitable cutting-edge. In the outer surface of each cutter is an indentation, *a''*, which provides a shoulder, *b''*. The dovetail form of the rear or inner side of the socket not only tends to hold the corresponding end of the cutter against any tendency to spring laterally outward, but also by acting upon the correspondingly-inclined extremities of the cutters serves to guide the same into the required positions and retain the two cutters with their edges on the same plane with much less liability to displacement than if reliance were placed wholly upon the dovetail longitudinal section of the socket. Furthermore, the rounded inner corners of the sockets are much less liable to chip off during the operations of inserting or removing the cutters, and, moreover, by lessening the frictional surfaces, permit the said removal or insertion, as the case may be, with a materially less application of force than would be the case if the corners were extended to sharp angles.

By inserting a suitable implement—as, for example, the blunt end of a cold-chisel—in the recess *a''* and bearing against the shoulder *b''*, each cutter may be driven out of its socket to permit its replacement or its substitution by another. This removal is facilitated by the peculiar shape or conformation of the socket and its contained cutter, hereinbefore explained, which said conformation also insures to the cutter when in place very firm retention in position and resistance to the thrust brought upon it in the operation of cutting wire or like articles in the ordinary uses of such implements.

What I claim as my invention is—

1. The combination of a cutter having dovetail ends and dovetail inner or rear end and rounded corners with a jaw, A, having a socket of corresponding form, all substantially as and for the purpose herein set forth.

2. The jaw of a cutting-plier, constructed with a socket having dovetailed ends and recessed at its inner side, as described, in combination with a cutter, B, of corresponding shape, substantially as and for the purpose herein set forth.

3. A cutter, B, having dovetail ends broadest at its cutting-edge and constructed with a

shouldered recess, a", in its outer surface, all substantially as and for the purpose herein set forth.

JOHN H. JENCKS.
